UNITED STATES PATENT OFFICE.

WILLIAM F. DAVIS, OF WATERLOO, IOWA, ASSIGNOR TO THE DAVIS GASOLINE ENGINE COMPANY, OF SAME PLACE.

GASOLENE AND GAS ENGINE.

SPECIFICATION forming part of Letters Patent No. 583,982, dated June 8, 1897.

Application filed May 31, 1895. Serial No. 551,325. (No model.)

To all whom it may concern.

Be it known that I, WILLIAM F. DAVIS, a citizen of the United States, residing at Waterloo, in the county of Black Hawk, State of Iowa, have invented certain new and useful Improvements in Gasolene and Gas Engines, of which I do declare the following to be a full, clear, and exact description, reference being had to the accompanying drawings, forming a part of this specification.

My present invention has for its object, primarily, to provide improved governor mechanism for gasoline and gas engines whereby the supply of oil or gas admitted to the cylinder of the engine can be more effectively controlled, and a further object of the invention is to provide improved means for effecting a better distribution of the gasoline, so that a more prompt and easy starting of the engine can be readily secured.

To this end the invention consists in the novel features of construction and combination of parts hereinafter described, illustrated in the accompanying drawings, and particularly defined in the claims at the end of this specification.

Figure 1 is a view in side elevation of a gasolene-engine having my invention applied thereto. Fig. 2 is a plan view of the engine. Fig. 3 is a detail view, in vertical section, through the hub of the fly-wheel and adjacent parts on line 3 3 of Fig. 1. Fig. 4 is a view in central section through the valve mechanism whereby the flow of gasoline is controlled, there being shown also in this view modified mechanism for operating the governor-valve. Fig. 5 is a plan view of the mechanism shown in Fig. 4. Fig. 6 is an end view of the mechanism shown in Figs. 4 and 5. Fig. 7 is a view in vertical section on line 7 7 of Fig. 5. Fig. 8 is a right-hand end view of the construction shown in Figs. 4 and 5. Fig. 9 is a view in central vertical section through the air-delivery pipe shown in Figs. 1 and 2. Fig. 10 is a view in horizontal section showing a modified form of valve mechanism to be employed when gas is used as the fuel.

By referring more particularly to Figs. 1 and 2 of the drawings, A designates the main frame of the engine, that rests upon a suit-

able base A', and B denotes the fly-wheel, that is fixed to one end of the main shaft B', the opposite end of this shaft being furnished with the usual belt-pulley B².

C and C' designate, respectively, the admission and exhaust valve chests, containing suitable valves whereby the admission and exhaust of the gas or vapor to and from the cylinder of the engine are controlled, these valves being operated by the pivoted levers c and c', which in turn are actuated by pitman-rods c² and c³, that connect with eccentric straps or yokes c⁴ and c⁵. The eccentric-yokes c⁴ and c⁵ are mounted upon eccentrics at each side of a gear-wheel D, that is journaled upon a suitable stud projecting from the main frame of the machine, and the gear-wheel D engages with a pinion d, fixed to the main shaft B' of the engine.

The mechanism for operating the admission and exhaust valves forms no part of the invention to be included in this application, and need not, therefore, be more particularly described, since the invention which I desire to protect herein is applicable to gas or gasoline engines in which many other types of admission and exhaust valves may be employed.

With the admission-valve chest C connects the mixing-pipe E, that may be of any suitable construction, although I prefer to employ the construction more particularly illustrated in Fig. 9 of the drawings. Into the pipe E (the construction of which will be hereinafter more particularly set forth) leads the fuel-delivery pipe F, whereby the supply of liquid fuel is delivered. The inner end of this delivery-pipe F is formed with a contracted seat f for a needle-point of the regulating-valve G. The outer end of the fuel-delivery pipe F is interiorly threaded, as at f', to receive the correspondingly-threaded part g of the regulating-valve G. The outer end of the regulating-valve G is furnished with a handle g', whereby the valve can be manipulated, and with a pointer g², extending inwardly adjacent a gage-plate F², with which the supply-pipe F is preferably provided. By means of the gage-plate F² and the pointer g² the setting of the valve G can be accurately determined. The inner end of

the fuel-supply pipe F is preferably screw-threaded to enter a correspondingly-threaded opening in the mixing-pipe E, although manifestly the manner of attaching the supply-pipe to the mixing-pipe is not essential to the main features of my invention. Upon the opposite side of the mixing-pipe E is formed an opening to admit the governor-valve H. If desired, the opening that receives the governor-valve H may be made in an extension that is formed in piece with the mixing-pipe E, as shown in Fig. 9 of the drawings, or the opening that receives the governor-valve H may be formed as a separate tube or casing H', as shown in Fig. 4 of the drawings, this tube H' being arranged to fit a corresponding opening in the side of the pipe E. Referring more particularly to Figs. 1, 2, and 9 of the drawings, it will be seen that the governor-valve H has its free end h arranged in opposition to the seat f of the regulating-valve G in order to control the flow of fuel through the seat f. Preferably the end of the governor-valve H is formed with a hole h' of sufficient size to clear the needle-point of the regulating-valve G, so as to permit the governor-valve to seat itself against the outer face of the valve-seat f. It is obvious, however, that if the point of the regulating-valve G were arranged to terminate inside the seat f the hole h' in the end of the governor-valve H would not be required. Upon the outer end of the casing that receives the governor-valve H (see Fig. 9) is mounted a coiled spring I, one end of which bears against a fixed shoulder and the opposite end of which bears against a flange or head h² at the outer end of the governor-valve H, this spring I thus serving to normally hold the valve H away from the seat f of the regulating-valve G.

In the accompanying drawings I have shown means whereby the regulating-valve H may be operated either from the fly-wheel B of the engine, as illustrated in Figs. 1, 2, and 9, or may be operated by a belt-pulley, as in the form of my invention shown more particularly in Figs. 4, 5, 6, and 7.

Referring to the construction illustrated in Figs. 1, 2, and 9, it will be seen that against the outer end of the governor-valve H bears an arm J, that is pivoted, as at j, to a projection from the main frame of the engine, the opposite end of the arm J being preferably yoke-shaped and pivotally connected by screws or pins to the sleeve K, that is loosely mounted upon the main drive-shaft B. (See Fig. 3.) Against the sleeve K bears a sliding sleeve k, with which engages an elbow-lever M, that is pivoted, as at m, to a projection b from the hub of the fly-wheel B, the opposite end of the elbow-lever M projecting through the fly-wheel and connecting to a rod M', that is united, as at m², to a weighted arm N, that is pivoted, as at n, to the rim of the fly-wheel B. From the rim of the fly-wheel B projects inwardly a lug b², against which bears one end of a coiled spring O, the oppo-

site end of this spring bearing against a washer o, that is fixed to the end of a rod O', that passes through the lug b², and is connected to the weighted arm N. The coiled spring O therefore serves to draw inward the weighted arm N against the centrifugal force incident to the revolution of the fly-wheel B.

From the foregoing description the operation of the parts thus far defined will be seen to be as follows, reference being had more particularly to the constructions shown in Figs. 1, 2, and 9 of the drawings. The regulating-valve G will be first set to admit the proper supply of oil through the fuel-delivery pipe F, it being understood, of course, that the oil is admitted to this pipe from a suitable source of supply, and it will be seen that as the oil is thus allowed to pass through the seat f of the regulating-valve G it will mingle in the pipe E with the supply of air admitted to this pipe. At such time the governor-valve H will be in the normal position seen in Fig. 9 of the drawings—that is to say, at a slight distance from the outer face of the seat f of the regulating-valve G; but inasmuch as the end of the governor-valve H is of such size as to completely close over the outer end of the valve-seat f it is manifest that no material obstruction of the flow of oil through the valve-seat f will occur until the end of the governor-valve H bears against the seat f, when the supply of oil through such seat will be completely shut off. Inasmuch as the oil is fed through the fuel-delivery pipe F under pressure, it will spray from the end of the valve-seat f, thus assisting the rapid evaporation of the oil, but the regulating-valve will afford a positive and steady feed that can be changed at will by the adjustment of the valve G, which can be set at any desired point. Inasmuch as the governor-valve H has its free end arranged immediately opposite and in close proximity to the seat f of the regulating-valve, there is practically no clearance between the governor-valve and the regulating-valve, and consequently there can never be any fluid playing between the two under variable pressure, but every drop of fluid that passes the seat f is under full pressure and is sprayed over the end of the governor-valve H and up and down the pipe E in every direction. So, also, it will be seen that inasmuch as the end of the governor-valve H is in such close proximity to the seat f of the regulating-valve the governor-valve will respond instantly to the actions of the engine and consequent speed of revolution of its fly-wheel. Hence it will be seen that if the engine is pulling, say, from one-third of a load up to a full load the inner end of the governor-valve H, responding to the speed of the fly-wheel B, will play loosely against or near the seat f of the regulating-valve, and thus allow the engine to take a charge of oil at regular intervals determined by the action of the admission-valve within the chest C; but if the engine is running light or doing prac-

tically no work the speed of the fly-wheel B, being correspondingly increased, causes the weighted arm N to be thrown outward under centrifugal force, and this shifting of the 5 weighted arm N in turn causes the lever J to act upon the outer end of the governor-valve H and forces this valve against the seat f of the regulating-valve and thus temporarily checks the flow of oil, so that the engine when thus running light will take a charge of oil with less frequency. This feature of locating the governor-valve in such proximity to the regulating-valve that it will respond promptly to the variations in the speed of the 5 engine, and in so doing speedily cut off the feed of oil for a limited time, is an important one, since the desideratum is not to throttle the oil-supply, but to completely shut it off when it is not required to maintain the speed 10 of the engine.

In the modified form of the invention illustrated in Figs. 4, 5, 6, and 7 of the drawings I have shown how my improved governor-valve mechanism may be controlled by the 5 action of a belt-governor instead of a fly-wheel governor, as hereinbefore described, and I wish it understood that the invention is designed to cover the governor-valve regardless of the particular kind of governor 15 that is employed for effecting its operation. In the modification last above mentioned the casing H', that sustains the governor-valve H, has mounted thereon a belt-pulley P, in manner free to revolve, and the hub p of this pulley is held against longitudinal movement upon the casing H' by means of a collar p', that is fixed to the outer end of the casing H'. From the outer end of the hub p of the pulley P project two pairs of arms p² and p³, and between these arms are pivotally sustained, as at r, the governor-arms R. The inner ends of the arms R are furnished with lateral projections or cross-heads r', (see Figs. 6 and 7,) through which pass the rods S, that carry the coiled springs s, each of these springs having one of their ends bearing against the adjacent cross-head r', while their opposite ends bear against suitable washers at the outer ends of the rods S. It will thus be seen that the springs s serve to normally hold the governor-arms R in the retracted position seen in Figs. 4, 6, and 7 of the drawings. The outer ends of the governor-arms R have inwardly-projecting portions r², that bear against a sleeve h⁴ at the outer end of the governor-valve H, this sleeve being preferably adjustably fixed to the end of the governor-valve H.

Between the sleeve h⁴ and the outer end of the casing H' is placed a coiled spring T, that serves to normally hold the governor-valve H in retracted position. From the foregoing description it will be seen that when the pulley P is revolved by a belt from the engine the governor-arms R will respond to the speed of revolution of the pulley P and of the engine,

these arms being thrown outward by centrifugal force against the resistance of the springs s. The outward movement of the governor-arms R will cause their extensions 70 r² to force inwardly the governor-valve H and to cause this valve to approach or recede from the seat f of the regulating-valve G. It will thus be seen that the governor-valve H will be caused to respond to the speed of the engine and will determine the feed of the oil through the fuel-supply pipe F in the same manner as in the construction hereinbefore described.

In the forms of my invention hereinbefore set forth I have shown the supply-pipe F and regulating-valve G as of a construction especially designed for engines in which oil is used as a fuel, but it is manifest that my invention may be employed in that type of engines in which gas is used as a fuel. I have therefore shown in Fig. 10 of the drawings a modified form of valve mechanism especially designed when gas is to be used. In this form of the invention the fuel-supply pipe F 90 has a contracted seat f for a regulating-valve G', the construction of this valve G' being the same as that of the valve G, hereinbefore described, except that its inner end is not pointed, but is simply furnished with a valve 95 to adapt it to close the seat f. The outer end of the valve G' is screw-threaded, but instead of engaging directly a threaded portion of the pipe F is shown as engaging a threaded coupling U, that is united to the outer end of 100 the pipe F. The coupling U is furnished with a dial, and the outer end of the valve G' will be provided with a handle having a pointer coöperating with the dial in order to enable the position of the valve G' to be accurately 105 determined. In this form of my invention the governor-valve H has its inner end suitably shaped to completely close the orifice of the seat f in the supply-pipe F. The operation of this form of valve will be readily understood from the operation of the several forms of my invention hereinbefore set forth.

While my invention is directed more especially to providing a governor-valve of the character hereinbefore set forth, I have provided also improved means for admitting air to the mixing-pipe E and improved means for effecting a better distribution of the oil-supply delivered to such pipe, and these features of my invention are illustrated more particularly in Figs. 1 and 9 of the drawings. At the base of the mixing-pipe E, I have provided a bowl V, that communicates freely with the pipe E. The bowl V may be connected with the pipe E in any convenient 125 manner, but I have shown the pipe E as furnished at its base with a flange E', that serves as a cover for the bowl V, and from the base E' depends an annular rim e, that extends to a point adjacent the bottom of the bowl V. 130 About the top of the bowl V are formed suitable openings v for the admission of the air-

supply, and the air thus admitted will be caused to pass downward beneath the depending rim *e* before it can enter the pipe *E*. The bottom of the bowl *V* is preferably raised, as shown at *V'*, so that any oil passing downward from the fuel-supply pipe *F* and not evaporated by the incoming air will accumulate around the outer portion of the bottom of the bowl *V*. It will be seen that by thus collecting the oil in the path of the incoming air-supply a full evaporation can be effected, and this feature is of importance, because as soon as the regulating-valve *G* is open and oil accumulates at the bottom of the bowl the supply of air admitted will be more thoroughly laden with the oil-supply, and consequently a more rapid starting of the engine can be had. After the engine has been started the regulating-valve *G* may also be temporarily closed until the incoming air has evaporated from the bowl the quantity of oil collected there. In case too great quantity of oil accumulates in the bottom of the bowl so as to charge the air-supply so strongly that it will not explode, the oil may be withdrawn from the base of the bowl through a suitable cock *v*², and this cock also serves to enable the operator to know positively whether the engine is being supplied properly with oil or not should he find trouble in starting. After the engine is started up and the accumulated oil at the bottom of the bowl *V* has been taken up by the air-supply the regulating-valve *G* will be again opened and will be allowed to so remain. Within the mixing-pipe *E*, I prefer to place one or more cores or spreaders *W* and *W'*, the purpose of which is to insure a more thorough exposure of the oil-supply to the action of the incoming air, and it will be seen that inasmuch as the oil admitted by the fuel-pipe *F* is sprayed in both upward and downward direction it will collect upon the cores *W* and *W'* and will be taken up by the air-supply during its passage through the mixing-pipe *E*. Each of the cores *W* and *W'* is preferably furnished with suitable arms or wings *w* to retain them in proper position within the mixing-pipe *E*.

It is manifest that the precise details of construction above set out may be varied within wide limits without departing from the spirit of the invention. It will be readily seen that if it is desired to convert an engine from a gas-engine to a gasoline or oil engine this can be readily accomplished by withdrawing the removable fuel-supply pipe *F* having a gas-valve and substitute for said fuel-supply pipe a similar pipe having a valve especially adapted for controlling the flow of gas.

Having thus described the invention, what I claim as new, and desire to secure by Letters Patent, is—

1. In apparatus of the character described, the combination with a fuel-supply pipe, of a

regulating-valve for controlling the flow of fuel through said pipe, a governor-valve located in proximity to the discharge end of said pipe and adjacent the seat of said regulating-valve, and a suitable governor mechanism for shifting said governor-valve.

2. In apparatus of the character described, the combination with a fuel-supply pipe, of a regulating-valve for controlling the flow of fuel through said pipe, said regulating-valve being located about the discharge end of said pipe, a governor-valve located opposite the discharge end of said fuel-supply pipe and in proximity thereto, and governor mechanism for operating said governor-valve.

3. In apparatus of the character described, the combination with an air-supply pipe and with a fuel-supply pipe or channel leading into said air-supply pipe, of a regulating-valve for said fuel-supply pipe and a spring-retracted governor-valve extending into said air-supply pipe at a point opposite the discharge-opening of said fuel-supply pipe into said oil-supply pipe, and governor mechanism for operating said governor-valve to close the discharge-opening in said fuel-supply pipe.

4. In apparatus of the character described, the combination with an air-supply pipe of a fuel-supply pipe leading into said air-supply pipe and detachably connected therewith, a regulating-valve within said fuel-supply pipe and a governing-valve for controlling the escape of fuel into said fuel-supply pipe, said governing-valve being located opposite the discharge side of said regulating-valve and adjacent the seat of said regulating-valve.

5. In apparatus of the character described, the combination with an air-supply pipe, of a bowl or oil-receptacle located at the base of said pipe and a deflecting-rim whereby the incoming air is directed toward the bottom of said bowl or receptacle.

6. In apparatus of the character described, the combination with an air-supply pipe, of a bowl or receptacle *V* located at the base of said air-supply pipe and having a raised central portion, and a depending rim or flange extending to a point adjacent the bottom of said bowl or receptacle and below the raised part of its bottom.

7. In apparatus of the character described, the combination with an air-supply pipe having an opening in its bottom for the admission of air and a fuel-supply pipe leading into said air-supply pipe at a distance above its bottom, of one or more cores or spreaders within said air-supply pipe, said cores or spreaders serving to expose the fuel-supply to the upwardly-passing current of air within the air-supply pipe.

WILLIAM F. DAVIS.
